[57] CLAIM

The ornamental design for an eye shadow applicator, substantially as shown and described.

DESCRIPTION

FIG. 1 is a front plan view of an eye shadow applicator, showing my new design;

FIG. 2 is a side elevational view thereof;

FIG. 3 is a top plan view thereof; the undisclosed bottom portion is a mirror image of the top shown;

FIG. 4 is a cross-sectional view of the applicator taken on the line 4—4 of FIG. 1.
